UNITED STATES PATENT OFFICE.

ERNEST SYDNEY HEURTLEY, OF LONDON, ENGLAND, ASSIGNOR OF ONE-HALF TO MUIRHEAD & COMPANY, LIMITED, OF ELMERS END, KENT, ENGLAND, A BRITISH COMPANY.

AUTOMATIC TELEGRAPHY.

Application filed April 9, 1923. Serial No. 630,771.

To all whom it may concern:

Be it known that I, ERNEST SYDNEY HEURTLEY, a subject of the King of Great Britain, residing at 4 Great Winchester Street, in the city and county of London, England, have invented certain new and useful Improvements in or Relating to Automatic Telegraphy, of which the following is a specification.

10 This invention relates to automatic telegraphy and has for its chief object to provide improved means by which in cable code signalling, employing the usual perforated slip, block or either block or beat signals can be transmitted, or, in an adaptation of the transmitter, retransmitted from an intermediate station.

According to this invention the pecker operated contact mechanism is arranged mechanically to maintain a marking contact made either for a positive or a negative signalling impulse until a space, or a marking contact of opposite polarity, intervenes. Thus if, say, two or three perforations follow in line on either side of the perforated slip the marking contact continues without interruption through the same number of time units, the contact being broken at the end of the succession of perforations by the corresponding pecker meeting an unperforated part of the slip at the next pecker operation or time unit. If the second pecker which is required for the marking contacts of opposite polarity meets at this time unit a perforation in the slip, a marking impulse of the opposite polarity is sent and this marking contact continues until the second pecker meets the unperforated slip. In retransmission the operation of the peckers would be effected through receiving electro-magnets under the control of the original transmitter.

While the pecker mechanism is arranged to send block signals a device may be provided to transform the block signals into beat signals should these be required, for which purpose a commutator or contact breaker may be provided, driven in synchronism so as to break contact or earth the cable once for each time unit.

In order that the said invention may be clearly understood and readily carried into effect, the same will now be described more

fully with reference to the accompanying drawings, in which:—

Figures 1 and 1^a are diagrams of a circuit and essential portions of the apparatus embodying this invention.

Figures 2 and 3 are respectively a front and side elevation of a transmitter illustrating a convenient construction by which the invention may be carried out; and

Figures 4 and 5 show the instrument adapted for retransmission.

A is the transmitter casing mounted on the base a, which also carries a motor B by which the transmitter is driven in a manner commonly employed. The motor shaft drives through the pinion b a toothed wheel c on the tape feeding shaft C, on the outer end of which is the star wheel c', engaging the central perforations of the tape in the usual manner as the tape passes over the platform a' of the casing under the roller a². D, D are the two peckers placed one behind the other and corresponding to two rows of perforations of the transmitting tape. The peckers are mounted on the ends of the levers d pivoted at d' on the end of an arm of the rocking bar E pivoted to the fixed bracket e and rocked through the connecting rod e' by the crank pin f on the shaft F. A large gear wheel G on the shaft C gears with the small pinion f' on the shaft F, the ratio shown being ten to one, so that the shaft F is driven at ten times the speed of the star wheel shaft C, the star wheel having ten teeth and the shaft F making one revolution for each movement of the tape from one perforation to the next.

Two contact levers H are provided, corresponding to the two peckers D, the front lever H being shown in Figure 2, the second lever being of similar type and lying immediately behind the front lever. The lever H is pivoted at h to the bracket h' which is connected up in the transmitter circuit and moves between the two adjustable contacts J, J. The lever is provided with a small bias device of usual type, comprising a spring h² and bias member h³ which holds the contact lever over in either position. The lever carries two arms K which are pivoted to it and are pressed against the central guiding roller k by the small springs k', the arms being adjusted so as to bring

the two outer ends opposite the ends d^2 of the corresponding pecker levers d . The ends d^2 are portions of the levers which are twisted round into the horizontal plane. 5 According to the position of a lever d its end d^2 will be opposite the end of either the upper or the lower arm K. The construction shown is on the lines of the Mur- 10 ray automatic transmitter, but in this case one contact lever and one pecker only are employed, whereas for the present system it is essential to employ two levers and peckers or their equivalent in order to send block 15 signals by cable code employing both positive and negative marking currents.

The general operation of the mechanism above described is as follows:—The rocking bars E which carry the pecker levers d are reciprocated at a constant rate from 20 the shaft F, driven, as already stated, at one revolution for each tooth movement of the wheel c' , that is, for each step of the transmitter tape. This reciprocation causes the levers d to move to and fro around their 25 pivots d' and consequently to cause the end d^2 of a lever to push over the arm K against which it may be set. If a pecker meets a 30 perforation in the tape it is allowed to move upwards sufficiently far to bring the end d^2 of its corresponding lever d against the end of the lower arm K on the contact lever H, and when the bar E rocks to the right the 35 lever d acting through the lower arm K will push over the contact lever H (assuming it is not already over) so that its contact end moves on to the left-hand contact J and it is held on this contact by the bias device as 40 long as no positive reversal is effected. If on further movement, either at the next or any succeeding step in the movement of the 45 tape, the same pecker meets an unperforated portion of the tape the lever d is caused to take the second position, in which the end d^2 lies against the end of the upper arm K. 50 In this position, when the rocking bar E moves forward the contact lever H is pushed over to the right on to the second contact J. If, however, the tape has two or more successive perforations at the same side the pecker D at the forward movement of the 55 rocking bar E still brings the lever end d^2 opposite the lower arm K and the contact lever H is unaffected. The action is precisely the same for both sets of peckers and pecker and contact levers, so that either 60 contact lever is moved over into marking position (or remains therein) for every perforation of the tape in the corresponding line, while for unperforated portions in both lines the contact levers are in non-marking or earthing position, or, should both lines of the tape be perforated at the same point and both contact levers move over to the marking contacts, the cable 65 would again be earthed, as will be explained

later with reference to the diagrams, Figures 1 and 1^a.

If it is desired to transform the block signals produced by the pecker and contact lever mechanism above described into beat signals, the contact breaker shown at the left of Figure 2 and in the diagram Figure 1 may be employed, or an equivalent commutator driven at the required speed and making a regular make and break in the 70 transmitter circuit. In the contact device shown, which provides for a variable marking for the beat signals, a rocking contact lever L is provided, pivoted at l on the adjustable support M carried on brackets m and adjustable longitudinally by the screw m' so that the pivot of the contact lever L can be moved to right or left for adjustment 75 purposes. The lower end of the lever L meets the contact m^2 and the circuit is completed through the support M and the lever itself, which is maintained in contacting position by the spring l'.

The contact of the lever L is intermittently broken by means of the cam N on the small shaft n provided with the pinion n' gearing with the larger gear wheel G and driven at the same rate as the pinion f' of the shaft F. Thus for every step of the 80 tape one revolution of the cam N is made and the cam is so spaced that the lever L is caused to break the circuit through a pre-determined portion of the revolution, the period of make and break determining the 85 marking percentage for the beat signals into which the block signals already provided for are broken.

To adjust the device to give the desired 90 marking percentage the pointer n^2 is set against the desired indication on the fixed 95 circular scale O, the transmitter being, of course, stopped. When the pointer is set to the required position by turning the gear 100 the support M of the lever L is adjusted until the lever just makes contact at m^2 when the other end meets the cam. When this adjustment is made the upper end of the lever L is on the portion of the cam N at which the breaking of the circuit is just about to begin and, therefore, the circuit is broken through such a portion of the revolution as is represented by the part of the cam at a greater distance from its axis, while contact is maintained throughout the remainder of the revolution, so that beats of any required 110 percentage are obtainable.

In Figures 4 and 5, which are detail views showing only the parts involved in the adaptation of the instrument for retransmission, Figure 4 being an elevation and Figure 5 a 115 plan, in place of the perforated slip mechanism the platform a' carries an electromagnet device operated by the incoming impulses, which may be in the form of the 120 usual beat signals produced by the ordinary 125 130

slip operated mechanism at the transmitting end. The peckers D, placed side by side as before, are each under the control of an armature S carried by an adjusting arm s mounted on the standard T and adjusted by the screw s' which bears on the carrier u of the electromagnet U. The armature S is controlled by the spring s² and when retracted by the spring the pecker D is free to move up, this position corresponding to a perforation in the slip, but when an impulse affects an electromagnet U the corresponding armature is pulled back and the pecker D is prevented from rising. The action of the armature on the pecker may of course be reversed and the pecker freed when the electromagnet is excited. The remaining operations are as already described for the original transmitter. As indicated in Figure 5 the retransmitting members are duplicated to provide for positive and negative marking impulses.

It is to be understood that the term pecker is employed to cover any reciprocated member which is controlled by the initial operating device such as the perforated slip or the electromagnet retransmitter.

In the arrangement shown in the diagram Figure 1, the transmission is effected through a pair of relays comprising the coils P and the armatures p, the latter moving between the two pairs of contacts p' which are connected to opposite ends of the sending battery Q. The transmitter circuit is provided with the local battery Q' connected at one end to the contact circuit breaking lever L under the control of the cam N and at the other between the relay coils P. The coils as shown are connected to the contacts J and the relay armatures p are connected respectively to earth and to line. If contact is made at either one of the contacts J and the lever L is also in contact making position a circuit is closed through one or other of the relay coils P and the corresponding armature is moved up, while the other armature remains down, so that a current is sent into line, either positive or negative, according to which armature is in marking position. If neither coil P is excited, that is, if the circuit is broken at both of the contacts J, both of the armatures p are down on the lower contacts p' and the line is, therefore, connected to earth. Also in the event of the circuit being closed at both of the contacts J both relay coils would be excited and both armatures p pulled up against the top contacts p', when again the line would be connected to earth. If the circuit breaking lever L is in operation then at each revolution of the cam N the local circuit would be broken over a predetermined fraction of the revolution and the line would immediately be earthed by the relay armatures p.

Figure 1^a shows circuits which may be used to effect transmission without the use of relays. In this case the lever L is directly connected to earth and moves between two contacts m², one earthed and connected to an earthed contact lever H while the other is connected to the second lever H. The sending battery Q² is connected up to the contacts J between which the levers H move and, as before, when both levers H are over 75 in the same direction on either pair of contacts the line is earthed while, if the levers are at different sides a positive or negative marking contact is effected, one side or other of the battery Q² being connected to earth 80 while the other side is connected to line so long as the lever L is against the upper contact m². If the interrupter is in operation the lever L is intermittently brought on to the lower contact m² by the action of the 85 cam N and the line is then earthed and the signals broken up into beat signals.

What I claim and desire to secure by Letters Patent of the United States is:—

1. In an automatic telegraph transmitter 90 adapted to send block signals, marking contact mechanism arranged to send both positive and negative signalling impulses, mechanical means whereby a marking contact made either for a positive or negative signalling impulse is maintained independently of the primary contact-making mechanism, and means for breaking the contact so maintained when a space or a marking contact of opposite polarity intervenes. 100

2. In an automatic telegraph transmitter adapted to send block signals, a plurality of peckers, a plurality of contact levers under the control of corresponding peckers, means interposed between the peckers and contact levers whereby the said levers may be operated positively in both directions and a mechanical retaining device for each contact lever, adapted to hold it over in marking position independently of the 110 position of its pecker until the said retaining device is positively operated mechanically in the opposite direction. 105

3. In an automatic telegraph transmitter adapted to send block signals, a plurality of 115 peckers, a plurality of corresponding marking contact levers adapted to be held in any position to which they are moved, and a regularly operated oscillating device adapted to actuate the said contact levers under 120 the control of their peckers, the position of which device relatively to a contact lever is determined by the position of the corresponding pecker.

4. In an automatic telegraph transmitter 125 adapted to send block signals, means driven in synchronism with the signalling mechanism by which a block signal may be broken up into a succession of beat signals, one for each time unit and occupying as a group 130

4
substantially the time interval of the said block signal.

5. In an automatic telegraph transmitter adapted to send block signals, a circuit interrupter driven in synchronism with the signalling mechanism and adapted to break up a block signal into a succession of beat signals, one for each time unit and occupying as a group substantially the time interval of the said block signal.

6. In a transmitter as claimed in claim 4, means for adjusting the beat signal forming device whereby any predetermined percentage of marking for each of the beat signals produced by breaking up the block signals is provided.

7. In an automatic telegraph transmitter adapted to send block signals, a circuit interrupter, a synchronously driven rotary device operating the said interrupter whereby the block signals may be divided up into beat signals, one for each time unit, and means for adjusting the interrupter relatively to the said rotary device to pro-

vide for any predetermined percentage of marking for the beat signals.

8. In an automatic telegraph transmitter adapted to send block signals by retransmission, a plurality of receiving electromagnets, marking contact mechanism under the control of the said receiving electromagnets adapted to send both positive and negative signalling impulses and mechanical means whereby the contact mechanism maintains a marking contact either for a positive or negative signalling impulse until a space or a marking contact of positive polarity intervenes.

9. In a transmitter as claimed in claim 8, a plurality of peckers operated by the corresponding receiving electromagnets, means for reciprocating the said peckers and movable members under the control of the electromagnets moved, according to the incoming signalling impulses, into and out of positions in which they co-operate with the said peckers.

ERNEST SYDNEY HEURTLEY.
